KNITTED FABRIC

James Everett Patton, Shelbyville, Tenn., assignor to Davenport-Woosley Processing Corporation, Chattanooga, Tenn., a corporation of Tennessee

Original application August 12, 1941, Serial No. 406,458. Divided and this application May 30, 1942, Serial No. 445,162

21 Claims.

(Cl. 66—187)

The present application is a division of a prior application Serial No. 406,458, filed by me on August 12, 1941.

This invention relates to knitted fabrics, and has reference more especially to flat knitted selvaged fabrics useful, for example, in the production of full fashioned stockings and the like, and characterized by having parallel edge portions as well as widened and narrowed portions with inclined edges.

Amongst the objects of my invention are to avoid sleaziness in the selvages of flat knitted fabrics of the kind referred to and at the same time increase resistivity to raveling, particularly along the edges of portions or sections which are reinforced by employment of an auxiliary yarn or yarns in the knitting, and which are progressively widened by the occasional addition of end loops. This desiderata I attain in practice as hereinafter more fully disclosed through a novel interlocking of the loops at the selvages at the fabric edges.

In connection with reinforced knitted fabrics having the above attributes, it is a further aim of my invention to reduce the thickness of the selvage edges with a view toward precluding bulky seams, when such edges are joined by overedge stitching as is ordinarily done in full fashioned hosiery production. This advantage I also realize in practice as more fully set forth later herein through formation of the end or selvage wale loops of the fabric either wholly or in part from one or the other of the two yarns used in knitting plain reinforced areas, or in the case of reinforced ringless fabric by similarly forming the end wales either wholly or in part from one of the several yarns used in the knitting.

Other objects and attendant advantages will appear from the following detailed description of the attached drawings, wherein

Fig. 1 is a fragmentary view of a full fashioned stocking blank formed from a flat knitted selvaged fabric conveniently embodying my invention.

Fig. 2 is a fragmentary detail view showing the exact formation of the selvage along the widened portion of one of the reinforced heel cheeks of the blank at the rectangle II in Fig. 1.

Fig. 3 is a view similar to Fig. 2 showing a slight variation in the selvage; and

Fig. 4 is a view in turn like Fig. 2 of knitted fabric formed in accordance with my invention as a ringless structure by use in the knitting of three main threads together with a reinforcing yarn.

The stocking blank exemplified in Fig. 1 may have a shaped leg portion (not shown) produced in the well known way from a single yarn and terminating in an ankle portion A, the direction of knitting being indicated by the arrow in the center of the figure. Beginning with the course B—B₃, the fabric is progressively widened for a time by addition of end loops along each edge to a course C—C'—C₂—C₃, with attendant formation of the upper portions of projecting heel tabs or cheeks at opposite edges of the blank having inclined selvages B—C and B₃—C₃. The web is next progressively narrowed as far as a line E—E'—E₂—E₃ for completion of the heel projections H, with incidental formation of lines C'—E' and C₂—E₂ of fashioning marks at complementary angles to selvage segments C—E and C₃—E₃, whereupon the foot of the stocking is knitted in a suitable manner with an instep portion I of uniform width to the line F—F₃ and with a tapered toe portion T therebeyond. If desired, a few courses of uniform width fabric may be knitted before transition from the widening to the narrowing at the apexes of the heel projections H to approximate a more rounded configuration in the latter. By use of two additional yarns in conjunction with a main yarn, I preferably reinforce the heel projections H as well as the side margins or sole areas of the foot as indicated by the wale line shading.

In Fig. 2 which shows a fragment of the widened portion of one of the heel cheeks H, certain wales of the web are designated by the numerals 1—7 and successive courses of the fabric by the numerals 21—33, while the main or body yarn is designated by the letter Y and the auxiliary or reinforcing yarn by the letter y.

From Fig. 2, it will be noted that in the lower parallel edged or ankle part A of the fabric fragment, selvage loops 41 are formed in the edge wale 4 in alternate courses 21 and 23 from the main yarn Y alone, and that in the penultimate wale 3 selvage loops 46 of the reinforcing yarn are doubled with plain loops 47 of the main yarn in the intervening courses 22 and 24, while in the remainder of such fabric portion plain loops 42 of said reinforcing yarn are doubled with plain loops 43 of said main yarn. In the first widened course 26 of the fabric in Fig. 2, a twisted loop 49 formed from one of the yarns, in this instance the main yarn Y, in the edge wale 5 is doubled with an untwisted loop 50 of the reinforcing yarn y, such selvage loop being locked by virtue of the passage of the main yarn Y through coincident sinker wale loops 51 and

52 of both yarns. The next widened course 30, has an untwisted loop 58 of the main yarn Y in the edge wale 7 doubled with a twisted loop 59 of the reinforcing yarn y. Here again it will be observed that the selvage loop 59 is locked by reason of the passage of one of the yarns, in this instance the reinforcing yarn y, through a sinker wale loop 60 formed from both yarns. Attention is directed to the fact that, in accordance with my invention, two extra end wale loops are added in the second step-out as distinguished from the addition of but one single loop in the first step-out in the course 26. Several unwidened courses 27, 28 and 29 may be interposed between the widened courses 26 and 30. In the course 27 it will be observed that the edge loop 53 in the wale 5 is formed solely from the main yarn Y, while in the next adjacent wale 4 in such course, a loop 55 of the reinforcing yarn y is doubled with a plain loop 54 of the main yarn. Beyond the widened course 30, the selvage loops 61 of the alternate uniform width courses 31 and 33 in the edge wale 7 are formed from the main yarn Y alone. In the intervening course 32, however, end selvage loops of the reinforcing yarn y are doubled with plain loops of the main yarn as instanced at 62. Beyond the course 33, it is to be understood that the double wale widening is repeated at suitably spaced intervals as often and to the extent desired or required, with maintenance of the above characteristic interlocking of the loops at the selvages.

The modified selvage of Fig. 3 is generally like the selvage of Fig. 2 except that in the second widening out course 30a (which corresponds to the course 30 in Fig. 2) an untwisted loop 59a of the reinforcing yarn y is doubled with an untwisted loop 58a of the main yarn Y' in the edge wale 7a. It is to be particularly observed that one leg of the loop 59a passes through double sinker wale loops of the main and reinforcing yarns at 60a in the course 31a, and that one leg of the loop 58a passes through a sinker wale loop of the reinforcing yarn only at 60a with consequent locking of the selvage against raveling at that region.

In Fig. 4, the three main yarns from which the fabric is produced as a ringless structure are designated respectively by the characters Y2, Y3 and Y4, and the yarn used in reinforcing by the character y2. As shown, the selvage formation of the fabric at the widened course 30b is similar to the selvage formation of the corresponding course 30 of Fig. 2 since it involves a twisted end loop 59b of the reinforcing yarn y2 which is locked through passage of such yarn through an adjacent sinker wale loop 60b, and which is doubled with a spread loop of one of the body yarns comprehending the two added end wales of the fabric. A slight variation will however be noted here in that the crosswise portion of the twisted loop 59b is within the sinker wale loop 60b and that the latter constitutes a loop in the succeeding course 31b. Except for longer skips of the main yarns at the selvages, the construction of the fabric of Fig. 4 is otherwise generally like that of Fig. 2.

From the foregoing it will be seen that in all the illustrated forms of my improved knitted fabric, the selvages are effectively locked against the possibility of easy raveling. It will also be seen that by forming the end selvage loops either throughout or in alternate courses from one only of multiple yarns employed in the knitting, the edge thickness in reinforced parts

is considerably reduced with consequent preclusion of bulky seams when such edges are united by sewing.

Having thus described my invention, I claim:

- 5 1. A flat straight-selvaged knitted fabric produced from two yarns, in which all the courses are reinforced by interknitting of the two yarns except at end loops in alternate courses, which end loops are formed from one of the two yarns only.
- 10 2. A flat straight-selvaged knitted fabric produced from two yarns, in which all the courses are reinforced by interknitting of the two yarns except at the selvage loops in alternate courses, which selvage loops are formed from one of the yarns only.
- 15 3. A flat knitted fabric with a widened reinforced selvage edge produced from two separate yarns, and having a widened course in which a twisted end loop of one yarn at such edge is doubled with an untwisted end loop of the other yarn.
- 20 4. A flat knitted fabric with a widened reinforced selvage edge produced from a main yarn and a reinforcing yarn, and having a widened course in which an untwisted end loop of the main yarn at such edge is doubled with a twisted end loop of the reinforcing yarn.
- 25 5. A flat knitted fabric with a widened selvage edge produced from two yarns and having a course widened one wale at said edge in which wale a twisted selvage loop of one yarn is doubled with an untwisted selvage loop of the other yarn, and in which course the first yarn passes through a sinker wale loop formed from both yarns adjacent said end wale loop in such course, while the second yarn passes to the outside of such sinker wale loop.
- 30 6. A flat knitted fabric with a widened selvage edge produced from a main yarn and a reinforcing yarn and having a course widened by one wale at said edge in which wale an untwisted selvage loop of the main yarn is doubled with a twisted selvage loop of the reinforcing yarn, and in which course the main yarn passes through a sinker wale loop formed from both yarns adjacent said end wale loop in such course, while the reinforcing yarn passes to the outside of said sinker wale loop.
- 35 7. A flat knitted fabric with a widened reinforced selvage edge produced from two yarns and having widened courses in which a twisted end loop of one yarn is doubled into coincidence with an untwisted end loop of the other yarn at such edge, and wherein said loops are both interengaged with two adjacent loops of both yarns in a succeeding course of the fabric.
- 40 8. A flat knitted fabric with a widened reinforced selvage edge produced from a main yarn and a reinforcing yarn, and having widened courses in which a twisted end loop of the reinforcing yarn is doubled into coincidence with an untwisted end loop of the main yarn at such edge, and wherein said loops are both interengaged with two adjacent loops in a succeeding course of the fabric.
- 45 9. A flat knitted fabric with a reinforced widened selvage edge produced from two separate yarns and having a widened course in the first step out at such edge wherein a twisted end loop of one yarn is doubled into coincidence with an untwisted end loop of the other yarn; and other widened courses in which a twisted end loop of one yarn is doubled into coincidence with an untwisted loop of the other yarn and the latter

loops both interengaged with two adjacent loops of both yarns in a succeeding course of the fabric.

10. A flat knitted fabric with a reinforced widened selvage edge produced from a main yarn and a reinforcing yarn, and having a widened course in the first step out wherein an untwisted end loop of the main yarn is doubled into coincidence with a twisted end loop of the reinforcing yarn; and other widened courses in which a twisted end loop of the reinforcing yarn is doubled into coincidence with an untwisted loop of the main yarn and the latter loops both interengaged with two adjacent loops in a succeeding course of the fabric.

11. A flat knitted fabric with a widened reinforced selvage edge produced from two yarns and having a course widened by two needle wales at said edge in the end wale of which course a twisted selvage loop of one yarn is doubled with an untwisted selvage loop of the other yarn, and in which the first yarn passes through a sinker wale loop formed from both yarns intermediate the two added needle loops in such course, while the second yarn passes to the outside of such sinker wale loop and through a sinker wale loop next adjacent the first mentioned sinker wale loop also formed from both yarns.

12. A flat knitted fabric with a widened reinforced selvage edge produced from a main yarn and a reinforcing yarn having a course widened by two needle wales at said edge in the end wale of which course a twisted selvage loop of the reinforcing yarn is doubled into coincidence with an untwisted selvage loop of the main yarn, and in which the reinforcing yarn passes through a sinker wale loop formed from both yarns intermediate the two added needle wale loops in such course, while the main yarn passes to the outside of such sinker wale loop and through an inwardly adjacent sinker wale loop also formed from both yarns.

13. A flat knitted fabric with a widened reinforced selvage edge produced from two separate yarns and having a course widened by two needle wales at said edge, in which course selvage loops of both yarns are interengaged with two adjacent loops in a succeeding course of the knitting, and in which a portion of one of such selvage loops extends through the sinker wale loop connecting the adjacent loops of said succeeding course.

14. A flat knitted fabric with a widened reinforced selvage edge produced from a main yarn

and a reinforcing yarn and having a course widened by two needle wales at said edge in which course selvage loops of both yarns are interengaged with two adjacent loops in a succeeding course of the knitting, and in which a portion of the selvage loop of the reinforcing yarn extends through the sinker wale loop connecting the adjacent loops of said succeeding course.

15. A flat knitted fabric with a widened reinforced selvage edge, produced as a ringless web from plural body yarns employed in succession in a repeating sequence in conjunction with a reinforcing yarn, wherein a twisted selvage loop formed from the reinforcing yarn in each widened course is doubled with a coincident untwisted loop formed from one of the body yarns.

16. A flat knitted fabric with a widened reinforcing selvage each produced as a ringless web from plural body yarns employed in succession in a repeating sequence in conjunction with a reinforcing yarn, wherein a widened course is extended by the distance of two wales, wherein a twisted selvage loop formed from the reinforcing yarn in such widened course is doubled with an untwisted coincident spread loop formed from one of said body yarns and comprehending the two added wales, and wherein the crossed portion of said twisted loop of the reinforcing yarn is locked through interengagement with the sinker wale intervening corresponding adjacent needle wale loops in the next succeeding course of the knitting.

17. A flat knitted stocking blank having widened lateral heel cheek projections at opposite edges with outwardly and downwardly sloped selvages characterized as in claim 2.

18. A flat knitted stocking blank having widened lateral heel cheek projections at opposite edges with outwardly and downwardly sloped selvages characterized as in claim 3.

19. A flat knitted stocking blank having widened lateral heel cheek projections at opposite edges with outwardly and downwardly sloped selvages characterized as in claim 10.

20. A flat knitted stocking blank having widened lateral heel cheek projections at opposite edges with outwardly and downwardly sloped selvages characterized as in claim 11.

21. A flat knitted stocking blank having widened lateral heel cheek projections at opposite edges with outwardly and downwardly sloped selvages characterized as in claim 15.

JAMES EVERETT PATTON.
